UNITED STATES PATENT OFFICE.

HAROLD G. BAXTER, OF BALDWIN, NEW YORK, ASSIGNOR TO WESTINGHOUSE ELECTRIC & MANUFACTURING COMPANY, A CORPORATION OF PENNSYLVANIA.

TUMBLER SWITCH.

Original application filed January 8, 1921, Serial No. 435,829. Divided and this application filed November 15, 1924. Serial No. 750,122.

To all whom it may concern:

Be it known that I, HAROLD G. BAXTER, a subject of the King of Great Britain, and a resident of Baldwin, Long Island, in the 5 county of Nassau and State of New York, have invented a new and useful Improvement in Tumbler Switches, of which the following is a specification, this application being a division of my application Serial 10 No. 435,829, filed Jan. 8, 1921.

My invention relates to electric switches and particularly to tumbler switches of the snap type.

One object of my invention is to provide 15 a snap switch of the tumbler type wherein the switch is caused to move to open or closed position with a snap action resulting from a minimum movement of the operating handle.

Another object of my invention is to provide 20 a snap switch having the above-noted characteristics wherein a minimum number of parts are required, and wherein the parts are inexpensive to manufacture and may be 25 readily assembled.

These and other objects that will be made 30 apparent throughout the further description of my invention, are attained by means of a switch construction hereinafter described 35 and illustrated in the accompanying drawings, wherein

Figure 1 is a side view, partially in elevation and partially in section, of a switch embodying my invention;

Fig. 2 is a view taken at right angles to that of Fig. 1;

Fig. 3 is a plan view; and

Fig. 4 is a partial plan view, showing some of the movable parts more in detail.

The switch is adapted to make and break 40 connection between stationary contact members 6 and 7, and consists of a pair of moving blades 8. The blades 8 are secured to a pair of blade carriers 9 by means of insulating member 10.

The carriers 9 are secured to a shaft 11 which is rectangular in cross-section. The shaft extends through a pair of holes in the sides of a frame member 12 of U-shape, 50 and is rotatable therein.

An operating lever 13 is pivoted on the frame at points 14 and 15 and carries a grip or handle member 16 at its upper end.

A cover plate 17, for connecting the side

members of the frame member 12, is provided with legends indicating whether the switch is in open position or in closed position and these legends are alternately covered and uncovered as the grip member is oscillated from one position to another, as indicated in Fig. 3.

Each of the blade carriers 9 is provided on its upper side with a pair of projections or lugs 18, and the lower end of the operating lever 13 is adapted to engage the lugs, as the lever is oscillated about the pivots 14 and 15, to impart positive movement to the blade carriers 9.

An eye bolt or spring-guide member 21 has one end pivoted to a shaft 19 carried by 70 the lever 13, and which extends through clearance slots 20 provided in the frame 12. The ends of the slots 20 serve to limit the movement of the operating lever 13. The other end of the bolt extends through a hole 75 22 of a bracket member 23, and a compression spring 24 is supported by the bolt and has its opposite ends in engagement with the bolt head and the bracket 23, respectively, in order to maintain a constant pressure 80 on said bracket.

The bracket 23 is secured to the shaft 11 and has a projection 23a adapted to engage a pair of turned lugs 25 on the frame 12 which serve to limit the movement of the 85 bracket 23.

With the parts in the position shown in Fig. 1, the spring is exerting tension in a direction to hold the switch-blade in engagement with the contact members 6 and 7. 90 If the handles 16 be moved to the left, the lower end of the operating lever 13 will engage a pair of lugs 18 and impart rotative movement to the blade carriers 9. These blade members, being non-rotatable with respect to the shaft, and the bracket 23 also being non-rotatable with respect to the shaft, the rotative movement is transmitted to the bracket 23, thereby carrying it from the position at the left of a vertical line through the shaft 11 to a position at the right thereof while, at the same time, the shaft 19 is carried to the right of a vertical line through the shaft 11. This changes the direction of force exerted by the spring 24 and causes 100 such spring to snap the blades to completely open position.

To return the blades to closed position,

the action just described is reversed, the 45
spring serving, in each instance, to complete
the movement of the blades by a snap action,
thus effecting a quick make and break action
and minimizing the tendency of the blades
and the stationary contacts to form arcs.

Various modifications may be made in the
construction without departing from the
spirit of the invention, as described in the
10 accompanying claims.

I claim as my invention:

1. In a snap switch, a frame, a switch
member pivoted thereto, an operating lever,
and a rod and spring connecting said lever
15 and said member, said member having two
projections and said lever having a projection
with a lost-motion connection with the
projections on said switch member.

2. In an electric switch, the combination
20 with a frame, of a pair of movable contact
members, carriers for the contact members,
a shaft pivoted in the frame and secured to
the carriers, a bracket secured to the shaft,
an operating lever pivoted to the frame, and
25 a compression spring having one of its ends
secured to the operating lever and its other
end abutting against the bracket, and means
whereby movement of the operating lever
shifts the position of the lower and upper
30 ends of the spring to change the direction of
pressure exerted on the bracket.

3. In an electric switch, a frame, a pair
35 of movable contact members, carriers for
the contact members, a shaft pivoted in the
frame and secured to the carriers, a bracket
secured to the shaft, an operating lever piv-
oted in the frame, and a compression spring
40 having one of its ends secured to the operating
lever and its other end abutting against
the bracket, and means for imparting move-
ment to the bracket to change the relative
angular position thereof with respect to the
45 spring.

4. In an electric switch, a frame, a mov-

able contact member, a carrier therefor, a 45
shaft pivoted in the frame and secured to
the carrier, a bracket secured to the shaft, a
spring guide having one end thereof pivoted
to the operating handle and its other end in
lost-motion engagement with the bracket, 50
and a spring carried by the guide and nor-
mally exerting a yielding force on the
bracket to maintain it in one of its extreme
positions, of means for shifting the point of
engagement between the spring guide and 55
the bracket.

5. In an electric switch, a frame, a shaft
pivotally supported thereon, a movable con-
tact member carried by the shaft, an op-
erating lever pivoted on the frame, and a 60
spring having one end supported by the
operating lever and the other end engaging
a bracket that is secured to the shaft and
normally exerting tension on said bracket
to maintain it in either of two extreme 65
positions of movement, of means whereby move-
ment of the operating lever imparts positive
movement to the blades and alters the direc-
tion of tension exerted by the spring on the
70 bracket, means limiting the range of move-
ment of the operating lever, and means lim-
iting the movement of the said bracket.

6. In an electric switch, a frame, a mov-
able contact member, a carrier for the con-
tact member, a shaft pivoted in the frame 75
and secured to the carrier, a bracket secured
to the shaft, an operating lever pivoted to
the frame, and a compression spring having
one of its ends secured to the operating lever
and its other end abutting against the brack- 80
et, and means whereby movement of the op-
erating lever shifts the position of the lower
and upper end of the spring to change the
direction of pressure exerted by the bracket.

In testimony whereof, I have hereunto 85
subscribed my name this 29th day of Octo-
ber, 1924.

HAROLD G. BAXTER.
